United States Patent Office

Des. 208,466
Patented Sept. 5, 1967

208,466

CHAIR BASE OR SIMILAR ARTICLE

Miguel Rodrigo, Republica de Chile St. 284, Lima, Peru

Filed Oct. 23, 1965, Ser. No. 87,871

Term of patent 14 years

(Cl. D15—2)

FIG. 1

FIG. 2

FIG. 3

FIG. 1 is a side elevational view of a chair base or similar article showing my design, the opposite not shown side of the chair base being a mirror image of the side shown;

FIG. 2 is a perspective view; and

FIG. 3 is a similar enlarged perspective view of said chair base.

The design is characterized by the channel-shaped configuration of the vertical post and outwardly extending leg members, as shown.

I claim:

The ornamental design for a chair base or similar article, as shown and described.
